UNITED STATES PATENT OFFICE.

JAKOB PFRETSCHNER, OF ESSEN, GERMANY, ASSIGNOR TO FRIED. KRUPP AKTIEN-GESELLSCHAFT, OF ESSEN-ON-THE-RUHR, GERMANY.

DEVICE FOR CUTTING AN INDUCTIVE RESISTANCE OUT OF CIRCUIT WITHOUT SPARKING.

Application filed September 26, 1921. Serial No. 503,251.

To all whom it may concern:

Be it known that I, JAKOB PFRETSCHNER, residing at Essen, Germany, a citizen of the German Republic, have invented 5 a certain new and useful Improvement in Devices for Cutting an Inductive Resistance Out of Circuit Without Sparking, of which the following is a specification.

This invention relates to a device for cutting 10 an inductive resistance out of circuit without sparking. Devices of this kind are described, for example, in application Ser. No. 437,888. This prior device is based upon the idea of connecting an auxiliary 15 resistance in parallel to the inductive resistance, to actuate an automatic circuit breaker, connected in series with the inductive resistance.

Now the object of the present invention 20 is to provide a device of this kind which, in comparison with the subject-matter of the above patent application is distinguished in particular by a still simpler manner of manipulation and greater reliability of work- 25 ing.

The invention will be described with reference to the accompanying drawing which shows diagrammatically an example embodying the subject-matter of the invention.

30 The inductive resistance A which is to be switched off, and which is formed, by way of example, by the winding of a magnet wound around an iron core, is connected in series to the gap contacts b^1 and b^2 35 of an automatic switch B, and also to the magnet winding d^1 of a switch D which can be switched on by hand. The magnet winding d^1 is provided for the purpose of holding the switch D, when switched on, 40 in the "on" position against the action of a tension spring d^2 , as long as a current flows through the inductive resistance A. It is not however capable of bringing the switch D into the "on" position. The 45 switch D is provided with two contacting elements d^3 and d^4 .

When the switch D is in its "on" position, the contact element d^3 bridges over a gap between the two switch contacts d^5 and 50 d^6 and provided in a conductor c^1 which contains an auxiliary resistance C. This conductor c^1 is connected in parallel to the inductive resistance A and the magnet winding d^1 in series therewith. At the

same time the contact element d^4 bridges 55 over a gap in a conductor E which is connected to the poles of a source of continuous current supplying the inductive resistance and contains the magnet winding b^3 of the automatic switch B already mentioned. 60

The switch B is provided with a pressure spring b^4 , acting in opposition to the magnet winding b^3 and has, in addition to a contact element b^5 intended to bridge over the gap b^1 b^2 in the main circuit two other 65 contact elements b^6 and b^7 which serve to bridge over gaps in each of two conductors F and G when the main circuit is opened by the switch B.

The conductor F, which contains the gap 70 f^2 f^3 adapted to be bridged over by the contact element b^8 is connected at one end to the positive pole of the source of current and at the other end to the switch block b^1 75 of the switch B. The conductor F also includes an auxiliary resistance f^1 . A second auxiliary resistance f^2 is placed in series with the conductor G, which contains the gap g^2 g^3 adapted to be bridged over 80 by the contact element b^7 and is connected at one end to the negative pole of the source of current and at the other end to that end of the magnet winding d^1 of the switch D which is remote from the inductive resistance A. 85

In the conductor G is placed in addition to the gap previously mentioned, a second gap bounded by two switch blocks g^4 and g^5 , and adapted to be bridged over by the contact element h^1 of a switch H, arranged 90 for two switch positions and operated by hand.

This switch H has a winding h^2 lying in the main current circuit, and a gap which is bounded by two switch blocks h^3 and h^4 95 which are connected in series with the magnet winding d^1 of the switch D, the inductive resistance A and the gap b^1 b^2 of the switch B. The purpose of the magnet winding h^2 is to hold the switch H, against 100 the action of a tension spring h^5 , in that switch position in which the gap h^3 h^4 is bridged over by the contact element h^1 , until the main current circuit containing the inductive resistance A and the magnet winding h^2 has become devoid of current. 105

For the two switches D and H which are to be operated by hand, there is provided

a common operating lever J which is capable of assuming three positions, and is so connected to the movable parts of the switches D and H that when it is moved over 5 out of its central position marked I in the drawing, into one of its two extreme positions marked II and III in the drawing, one of these two switches is moved into the "on" position and when moved over into the other 10 extreme position the other switch is moved over into the "on" position, the respective tension spring being tensioned. A flat spring i^1 mounted on the operating lever J causes the latter to always return to its 15 central position I as soon as it is released.

The description of the working of the above described arrangement will be commenced from the position shown in the drawing, in which position all parts of the 20 device, and in particular therefore also the inductive resistance A, are without current and the operating lever J is in its central position (I).

Supposing the inductive resistance A is 25 now to be switched on, the operating lever J is moved over into position II and then released so that it returns to position I under the action of the flat spring i^1 . At the same time the switch H is brought into 30 the position in which the contact element h^1 bridges over the gap $h^3 h^4$ in the main current circuit. A current thus flows through the main current circuit $+ h^2 h^3 h^1 h^4 d^1 A b^1 b^6 b^2 -$, which supplies the inductive resistance A and excites the magnet windings d^1 and h^2 . The magnet winding h^2 is of such construction that it holds 35 the raised switch H in the position in which it bridges over the gap $h^3 h^4$ even after the return of the operating lever J to its central position marked I.

On the other hand the magnet winding d^1 is unable to move the switch D into its "on" position as the reluctance of the magnetic circuit of the switch D, when in the 45 "off" position, is too great for it to do so.

Supposing now the inductive resistance A is to be switched off, the operating lever J is moved over into the position marked 50 III and released. The switch D then passes into the position, in which the contact element d^3 bridges over the gap $d^5 d^6$ and at the same time the conductor E containing the magnet winding b^3 of the automatic 55 switch B is closed by the contact element d^4 .

The bridging over of the gap $d^5 d^6$ connects up the auxiliary resistance C in 60 parallel with the inductive resistance A and with the magnet winding d^1 connected up in series with the latter. In consequence of the excitation of the magnet winding b^3 the switch B is switched off against the action of the spring b^4 , which latter is now compressed 65 and the contact element b^5 is displaced from

the switch blocks $b^1 b^2$. Simultaneously the contact elements b^6 and b^7 bridge over the gaps provided in the conductors F and G, viz., $f^2 f^3$ and $g^2 g^3$ and thereby prepare for the switching into circuit of the auxiliary 70 resistances f^1 and g^1 .

In consequence of the interruption of the main current circuit by the switch B the inductive resistance A is switched off from the source of current. Notwithstanding no 75 sparking occurs at the gap $b^1 b^2$, because the circuit $A c^1 C d^8 d^3 d^5 c^1 d^1 A$ presents a closed path to the induction current produced on the breaking of the circuit. As long as the induction current which flows 80 through the inductive resistance A in the same direction in which the main current previously did, still possesses any appreciable strength, the switch D is held in the "on" position by the magnet winding d^1 . 85

At the moment of the breaking of the main current circuit by the switch B the magnet winding h^2 is also deprived of current, so that the switch H returns to its position shown in the drawing, under the action of the tension spring h^5 . In this position the contact element h^1 bridges over the one gap $g^4 g^5$ still left open in the conductor G so that a current flows for a short time in the circuit $+ F f^1 f^2 b^6 f^8 A d^1 G g^5 h^1 g^4 G g^1 g^8 b^7 g^2 G E -$ which passes through the inductive resistance A in the opposite direction to that of the induction current and of the main current preceding it. The magnetism which may still exist in the iron core 90 of the inductive resistance A including the residual magnetism can thereby be effectively destroyed.

As soon as the induction current in the circuit $A c^1 C d^8 d^3 d^5 c^1 d^1 A$ has died down and the residual magnetism in the inductive resistance A has been destroyed the switch D, which is no longer held by the magnet winding d^1 , returns under the action of the tension spring d^2 to its "off" position shown 100 in the drawing. This causes the conductor c^1 containing the auxiliary resistance C to be interrupted, while on the other hand the conductor E with the magnet winding b^3 , becomes deprived of current so that the automatic switch B also returns to the position shown in the drawing, under the action of the pressure spring b^4 . Then the auxiliary resistances f^1 and g^1 are also switched off 110 from the source of current and the inductive resistance A and the device is once 115 more ready for use.

The simple manner of manipulation and the great reliability of working brought 120 about thereby is based upon the fact that the present device can be specially well combined with a switch device J i^1 which while being free from all possibility of being 125 wrongly manipulated, permits of the connection, by one switch movement, firstly of 130

the inductive resistance A and secondly, by a second switch movement, of the magnet winding b^8 of the automatic switch B, to the source of current.

5 A further advantage of the hereinabove described device consists in the fact that the points of connection of the conductors F and G which supply the demagnetizing current are formed by the switch blocks b^1 and h^4 , 10 so that only the ends of the inductive resistance need to be accessible, while a third connection in the middle of the inductive resistance heretofore disclosed is superfluous.

15 The arrangement of two auxiliary resistances f^1 and g^1 which can be connected up in series, instead of only one such resistance offers finally the advantage that short-circuits across the conductors F and G can be effectually avoided even in the case that a 20 spark produced on switching off remains between b^8 and $b^1 b^2$ or between h^1 and $h^8 h^4$.

Claims:

1. In combination with an inductive resistance connected in a main circuit, a resistance element connected in shunt with said inductive resistance, a switch in said shunt circuit, an electro-magnetically controlled switch in said main circuit, means for exciting the windings of said electro-magnetically controlled switch from said main circuit, a switch for controlling said excitation and common means for controlling said last named switch and said shunt circuit switch whereby they being closed, said main circuit switch is opened.

2. In combination with an inductive resistance connected in a main circuit, a resistance element connected in shunt with said inductive resistance, a switch in said shunt circuit, a switch in said main circuit, means for automatically opening said main circuit switch consequent to closing said shunt circuit switch and means for opening said shunt circuit switch and closing said main circuit switch when a current no longer exists in said shunt circuit.

3. In combination with an inductive resistance connected in a main circuit, a switch in said main circuit a resistance element connected in shunt with said inductive resistance, a switch in said shunt circuit, means for closing said shunt circuit switch and simultaneously opening said main circuit switch, a coil in series with said inductive resistance and said shunt circuit for holding said shunt circuit switch closed and means for opening said shunt circuit switch when a current no longer exists in its circuit.

4. In combination with an inductive resistance connected in a main circuit, a resistance element connected in shunt with said inductive resistance, a switch in said shunt circuit, a switch in said main circuit, means for automatically opening said main circuit switch consequent to closing said

shunt circuit switch and means for sending a current through said inductive resistance in reverse direction to the main circuit current when said shunt circuit switch is closed.

5. In combination with an inductive resistance connected in a main circuit, three auxiliary circuits, means whereby the main circuit being broken, one of said auxiliary circuits forms a closed circuit with said inductive resistance and means whereby the 70 main circuit being broken the other two auxiliary circuits cooperate in supplying said inductive resistance with a current in reverse direction to the main circuit current.

6. In combination with an inductive resistance connected in a main circuit, three auxiliary circuits, a resistance element in each of said auxiliary circuits, means whereby the main circuit being broken, one of said auxiliary circuits forms a closed circuit with 75 said inductive resistance and means whereby the main circuit being broken, the other two auxiliary circuits cooperate in supplying said inductive resistance with a current in reverse direction to the main circuit current.

7. In combination with an inductive resistance connected in a main circuit, a switch in said main circuit, a second switch in said main circuit, a shunt circuit in connection with said main circuit and bridging

80 said inductive resistance and one of said switches, a second shunt circuit in connection with said main circuit and bridging said inductive resistance and the other of said switches, a switch in each of said shunt circuits, and means for opening said main circuit switches and closing said shunt circuit switches, whereby a current in reverse direction to said main circuit current is led to said inductive resistance through one of 85 said shunt circuits and led away through the other of said shunt circuits.

8. In combination with an inductive resistance connected in a main circuit, a switch in said main circuit, a second switch in said main circuit, a shunt circuit in connection with said main circuit and bridging said inductive resistance and one of said switches, a second shunt circuit in connection with said main circuit and bridging 90 said inductive resistance and the other of said switches, a switch in each of said shunt circuits, a resistance element in one or both of said shunt circuits, and means for opening said main circuit switches and closing 95 said shunt circuit switches whereby a current in reverse direction to said main circuit current is led to said inductive resistance through one of said shunt circuits and led away through the other of said shunt circuits.

9. In combination with an inductive resistance connected in a main circuit, a switch in said main circuit, a second switch in said main circuit, a shunt circuit in connection 100

with said main circuit and bridging said inductive resistance and one of said switches, a second shunt circuit in connection with said main circuit and bridging said inductive 5 resistance and the other of said switches, a switch in each of said shunt circuits, a coil in said main circuit for holding one of said main circuit switches, a coil excited from said main circuit for operating the other of 10 said main circuit switches and the shunt circuit switches, a switch for controlling the excitation of said coil whereby said operating coil being excited, the main circuit switch under its control is opened, said shunt circuit 15 switches are closed, and said holding coil is de-energized, allowing said other main circuit switch to open, whereby a current in opposite direction to the main circuit current is supplied to said inductive resistance through said shunt circuits. 20

10. In combination with an inductive resistance, a source of current, three auxiliary circuits, a control lever, means whereby said control lever being moved in one direction, connection is made between said inductive 25 resistance and said source of current, and means whereby said control lever being moved in the opposite direction said connection is broken, one of said auxiliary circuits is connected in shunt with said inductive 30 resistance, and the other two auxiliary circuits are brought into cooperation with said source of current and said inductive resistance whereby a current in a direction reverse to that of said source of current is 35 supplied to said inductive resistance.

The foregoing specification signed at Essen, Germany, this 30th day of August, 1921.

WOB PFRETZSCHNER.
